GLASSWORKING APPARATUS

David E. Gray, Corning, N. Y., assignor to Corning Glass Works, Corning, N. Y., a corporation of New York

Application May 8, 1942, Serial No. 442,241

8 Claims. (Cl. 49—1)

The present invention is directed to apparatus especially suitable for reheating and reshaping of glass parts and also for fusing glass parts to one another to produce articles of configurations not readily produced by other methods.

The invention is, by way of example, embodied in a structure suitable for performing glazing operations.

In the drawings,

Fig. 1 is a side elevation, partly in section, of a structure embodying the invention;

Fig. 1a is an enlarged side elevation, in section, of a fragment of the structure of Fig. 1;

Fig. 2 is an enlarged fragmentary view, partly in section, of apparatus of Fig. 1 but with the parts shown in different position;

Fig. 2a shows a fragment of a sheet of glass and a sectional plan view of an electrode;

Fig. 3 is a sectional view taken on line 3—3 of Fig. 1;

Fig. 4 is a sectional elevation along line 4—4 of Fig. 3;

Fig. 5 is a view partly in section of the apparatus of Fig. 2 shown in a different operating position.

The apparatus includes a suitable upstanding frame 11 having a kiln 12 arranged intermediate its ends adapted to be heated to any desired temperature by a plurality of heating elements such as the element 13 shown, connected through automatic temperature control mechanism to a suitable source of electric energy.

Arranged in the lower part of frame 11 is a base 14 supporting a tubular column 15 surrounded by a sleeve 16 pivotally supported on a hand lever 24 and having web members 17 which accommodate rods 18. Rods 18 pass through the bottom wall of kiln 12 and within the kiln support a vacuum chuck 19 having a face 21 composed of a highly refractory electric insulating material. A pipe 22 and a flexible hose 23 are employed to establish communication between the chuck 19 and a suitable vacuum line (not shown). By disconnecting pipe 22 from the chuck 19 the same can readily be lifted from rods 18 and replaced with another. Lowering or raising of the chuck 19 can be accomplished by actuation of hand lever 24 which is suspended from the back of frame 11 by a link 25 and movably held to the front of the frame 11 by a latch 26.

Arranged in the upper part of frame 11 is a bridge member 31 held by adjusting screws 28. A tubular guide shaft 32 depends from member 31 into the kiln and has a chuck 33 removably attached thereto in a manner made evident here-

inafter. Chuck 33 is provided with a refractory face 34 of insulating material and is aligned over chuck 19. By suitable adjustment of member 31 the face 34 can be brought into a plane parallel to that occupied by face 21. Shaft 32 at its upper end is connected with a hose 35 in communication with a vacuum line (not shown). Surrounding shaft 32 is a sleeve 36 pivotally supported at its upper end on a hand lever 37 suspended from a link 38 attached to a bridge member 31. The lower end of sleeve 36 is surrounded by a flange 57 integral therewith and adapted to fit into the hub of a lever supporting and actuating spider 40 having cleats 48 (Figs. 2, 3, and 4) integral therewith. Wedges 54 driven between cleats 48 and flange 57 hold the spider 40 rigidly to the sleeve 36, while enabling easy removal thereof and replacement even while the parts are hot. As will be apparent from an inspection of the drawings the chuck 33 is attached to member 32 in a similar manner. Lever supporting and actuating spider 40 has pierced ears 41 from which links 42 are suspended. The lower ends of links 42 are pivotally attached to folding bar supports 43 which at 44 are pivotally connected to the lower ends of links 45 which have their upper ends pivotally connected to upright supports 46 forming part of the chuck 33. Although the links 42 and 45 prevent turning movement of the spider 40 relative to the chuck 33 alignment is positively maintained by a vertical guide post 49 threaded into one of the upright supports 46 and extending upward through an aperture through spider 40.

Attached to the under side of supports 43 are folding bars 50 and 51 certain ones of which have depending sheet aligning fingers 52. The couplings between the links 42, supports 43 and links 45 are such that as the sleeve 36 is lowered, supports 43 are moved inward toward the chuck 33 until links 45 engage pads 47 formed on the uprights 46. If an appropriate size sheet of glass is being held by chuck 33 the above described movement of supports 43 brings bars 50 and 51 adjacent and slightly above the edges of the sheet. As lowering of sleeve 36 continues link 45 remains stationary and accordingly the supports 43 turn about their pivots 44 away from engagement of their back stops 55 with links 45 and are brought to a stop by engagement of their stops 53 with links 45. As an inspection of Fig. 4 will show during this second stage of operation of supports 43 the folding bars 50 and 51 move through the path required to perform a folding operation. Also the above described movement

of bars 50 and the rear bar 51 brings fingers 52 into a vertical position enabling them to perform a sheet aligning function as will be brought out later.

The levers 24 and 37 opposite their handle ends are connected together with a slotted link 39 which serves to actuate lever 37 to raise sleeve 36 in case lever 24 is actuated to raise chuck 19 when the sleeve 36 is in its down position. This removes the danger of damage to fingers 52 or to glass on platen 21 by fingers 52 as might occur were it possible to raise the platen into engagement with the fingers.

Also arranged in the upper part of frame 11 is an electrode supporting frame 60 suspended from a balanced lever 61 by means of which the frame can be raised and lowered at will. An arm 61' has one end pivoted to frame 11 and the other end pivoted to frame 60 a distance below the pivoted connection of lever 61 to keep frame 60 level. The upper end of frame 60 is bridged by strips of electrical insulation 60' through which electrodes 63 pass down through bushings 62 at the lower end of the frame and downward through bushings in the upper wall of kiln 12 a distance depending upon the setting of collars 65 secured to the electrodes 63 and resting upon bushings 62. The passages through the bushings in the wall of kiln 12 through which electrodes 63 pass are of such size as to provide ample clearance for the unobjectionable slight arcuate movement of the electrodes which occurs as they are being raised or lowered. A door 64 gives access to the interior of kiln 12 and is provided with a window 66 to enable an operator to observe the operations being carried out within the kiln with the door closed.

In employing the foregoing apparatus in the production of a double glazed cell, two sheets of glass 70 and 71 (Fig. 1) are arranged on chuck face 21 with lever 37 raised slightly from the position it is shown in Fig. 1 at which time fingers 52 will not quite have reached the vertical position in which they are shown in Figs. 1 and 4, so that the sheets 70 and 71 can readily be placed on the chuck and moved toward the rear thereof until stopped by the rear fingers 52. With sheets 70 and 71 so placed on chuck 19 the completion of the lowering of lever 37 will cause fingers 52 to attain their vertical position, moving with them sheets 70 and 71 as necessary to bring them into exact vertical alignment. The lower ends of fingers 52 are cut back at 52' a distance corresponding to the difference in size of sheets 70 and 71 so that with fingers 52 in the vertical position the bounding edges of the upper sheet are uniformly spaced within the bounding edges of the lower sheet. The lever 37 should next be lifted to bring fingers 52 to the position illustrated in Fig. 2, to prepare for the transfer of sheet 70 to chuck 33. The transfer is accomplished by first applying vacuum to both chucks and then raising lever 24 until sheet 70 is engaged and seized by chuck 33 after which lever 24 is returned to its lowermost position. Should the operator fail to raise lever 37 prior to raising lever 24 lever 37 will be automatically raised by link 39 as lever 24 is raised, as already described.

The lever 61 is next shifted as required to bring the electrodes 63 into contact with the edge surface of the cutaway corners of sheet 70, as illustrated in Fig. 2a and the necessary current applied to heat and soften the marginal portions of sheet 70. When the marginal edges of the sheet have become suitably plastic the current supply 75

is cut off and lever 37 lowered to move the folding bars 50 and 51 from the positions shown in Fig. 2 to those shown in Fig. 4 after which lever 37 is again raised to restore the bars to the position shown in Fig. 2. The sheet 70 is thus formed into a shallow inverted container in readiness to be sealed to the upper surface of sheet 71. Sealing is accomplished by moving lever 24 as required to raise sheet 71 into contact with the down turned edges of sheet 70 followed by application of the necessary sealing current to electrode 63. Pulling of the seal and freeing of the electrodes from the completed unit can be readily accomplished by proper manipulation of levers 61 and 24.

To prepare for the removal of a completed unit from kiln 21 chuck 33 is connected to atmosphere and chuck 19 lowered and connected to atmosphere. Removal of the unit may now be readily effected by its seizure with a portable vacuum chuck which can conveniently be employed to transfer the unit to a suitable annealing lehr.

Although in the foregoing there has been shown and described the preferred embodiment of my invention as designed for use in producing double glazed cells of a simple form, it should be understood that changes in the details of construction and combination of parts to render the same suitable for sealing other forms of articles may be resorted to without departing from the spirit and scope of my invention as claimed.

What I claim is:

1. In a glass working apparatus, a kiln, a pair of vertically aligned chucks arranged within the kiln, and means associated with the upper chuck for shifting an article arranged on the lower chuck to a predetermined position with respect to said chucks.

2. In a glass working apparatus, a kiln, a pair of vertically aligned chucks arranged within the kiln, means associated with the upper chuck for shifting an article arranged on the lower chuck to a predetermined position with respect to said chucks, and means for manipulating said lower chuck to transfer the article to the upper chuck.

3. In a glass working apparatus, a kiln, a pair of vertically aligned chucks arranged within the kiln, means associated with the upper chuck for shifting an article arranged on the lower chuck to a predetermined position with respect to said chucks, a plurality of electrodes, and means for moving said electrodes into contact with predetermined surface areas of an article held by one of said chucks.

4. In a glass working apparatus, a kiln, a pair of vertically aligned chucks arranged within the kiln, means associated with the upper chuck for shifting an article arranged on the lower chuck to a predetermined position with respect to said chucks, a plurality of electrodes arranged around said upper chuck, and means for bringing said electrodes into contact with edge surfaces of an article associated with said upper chuck.

5. In a glass working apparatus, a vacuum chuck arranged to hold a sheet of glass flatwise in a horizontal plane, electrodes arranged for association with edge portions of the sheet adapted to supply current to heat the marginal portions of the sheet to plasticity, folding bars arranged above the marginal portions of the sheet, and means for swinging said bars down over the edges of the sheet in such a manner that they fold the marginal portions into a plane normal to that of the sheet.

6. In a glass working apparatus, a vertically

disposed tubular member having a chuck arranged on its lower end adapted to hold a sheet of glass flatwise in a horizontal plane, means associated with said chuck for heating a marginal portion of a glass sheet held by said chuck to plasticity, a sleeve surrounding said member, a mechanical linkage extending between said chuck and sleeve, a glass reshaping element carried by said linkage, and means for effecting relative movement between said sleeve and chuck to actuate said linkage to move said shaping element to reshape the heated marginal portion of the sheet.

7. In a glass working apparatus, a kiln, vertically aligned chucks arranged to hold sheets of glass flatwise in horizontal planes within said kiln, means external of the kiln for moving one of said chucks with respect to the other whereby a sheet in one chuck can be brought into contact with a sheet in the other chuck, means for heating the marginal edges of a sheet of glass held by the upper chuck until such edges sag toward the sheet of glass in the lower chuck, implements within said kiln for folding the softened mar-

ginal edges of the upper sheet into planes normal to the sheet, and means external to said kiln for operating said implements, the means for heating being also available for fusing together the two sheets of glass after being brought into contact with one another.

8. In a glass working apparatus, a kiln, a pair of aligned chucks within said kiln, fingers within said kiln, means including a manually operable device for moving said fingers to align sheets of glass associated with one of said chucks in a predetermined lateral position with respect thereto, means for heating the marginal portion of a sheet of glass held by one chuck to plasticity, implements also operable by said first means to bend the marginal portions of the sheet so heated toward a sheet held by the other chuck, and means external to said kiln for moving one chuck relative to the other to bring glass sheets held by said chucks into contact with one another, said means for heating being subsequently available for fusing together the contacting glass.

DAVID E. GRAY.
